CLAIM

(30) **Foreign Application Priority Data**

The ornamental design for a writing utensil with push button component, as shown and described.

Jun. 5, 2000 (DE) 4 00 05 315
Jul. 14, 2000 (DE) 4 00 06 630

DESCRIPTION

(51) **LOC (7) Cl.** **19-06**

FIG. 1. A front perspective view of the writing utensil with push button component showing my new design;

(52) **U.S. Cl.** **D19/46; D19/49; D19/56**

FIG. 2. is a rear perspective view thereof;

(58) **Field of Search** D19/35, 36, 41-49,

FIG. 3. is a side elevational view thereof;

D19/50, 51, 53-58, 81-85; 401/99, 100,
103-106, 110-117, 209; 24/11 F

FIG. 4. is a rear elevational view thereof;

(56) **References Cited**

FIG. 5. is a front elevational view thereof;

U.S. PATENT DOCUMENTS

FIG. 6. is a side elevational view thereof;

1,125,144 A * 1/1915 Mabie ..... 24/11 F
D59,035 S * 9/1921 Sheaffer D19/46
